Primary Examiner — Abraham Bahta(74) *Attorney, Agent, or Firm* — Wilson Sonsini Goodrich & Rosati(57) **CLAIM**

The ornamental design for a dermatology report document, as shown and described.

DESCRIPTION

The sole FIGURE is a front view of a dermatology report document, showing our new design.

The peripheral broken lines represent an unclaimed boundary of the dermatology report document and form no part of the claimed design. Within the peripheral broken lines, the broken line showing of text and other features of the dermatology report document is for environmental purposes only and forms no part of the claimed design. The difference in crosshatch shading indicates a contrast of appearance and does not depict any particular color, texture, or material. The dermatology report document has no appreciable thickness.

Referring Physician:	Fax Number:		
Address:	City/State/Zip:		
TEST RESULTS			
Gene Expression Status: Positive		LINC00518: Detected PRAME: Not Detected	
Risk Status: Moderate (Orange)			
Expression of LINC00518 and/or PRAME is found in lesions with a histopathologic diagnosis of melanoma. If one or both of the genes are detected, the test is positive.			
Macro-dissection Report/Comments: The pre-specimen consists of adhesive patches containing four tissue samples. Except as noted, each patch contained tissue material which was free of obvious contamination with blood, exudate, hair or other contaminants. Each patch had a central circle delineating the margin around the tissue material. Examination of each of the macrodissected specimen revealed that the lesional tissue material was excised at the margin. Each sample was submitted for qPCR analysis. Images of all 4 of the macrodissections are kept on file and are available for review.			
Interpretation:			
	LOW (GREEN): Melanoma associated gene expression negative. Consider surveillance per standard of care.		
	MODERATE (ORANGE): Positive for a single gene (LINC only or PRAME only). Recommend biopsy and histopathologic assessment. The proportion of pigmented lesions that are histopathologically diagnosed as melanoma is lower in single gene positive samples (50% for PRAME only positives and 7% for LINC only positives) than in double gene positive samples.		
	HIGH (RED): Positive for both LINC and PRAME genes. Recommend biopsy and histopathologic assessment. The proportion of pigmented lesions that are histopathologically diagnosed as melanoma is higher in two gene positive samples (93% for both LINC and PRAME positives) than in single gene positive samples.
